UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 19, 1929. Serial No. 415,170.

This invention relates to improvements in car construction.

One object of the invention is to provide a combined locking center pin for connecting the body and truck bolsters of a railway car, which may be readily applied and removed, and is of rugged design having exceptionally great tensile strength and resistance to shearing action, including a main connecting member and a locking member, wherein both members are provided with shank portions extending through the pin receiving openings of the bolsters, the shank portion of the connecting member embracing the shank of the locking member to reinforce the same and the two shank portions together forming the complete shank of the pin.

Another object of the invention is to provide a center pin of the character described in the preceding paragraph, wherein the connecting member is provided with head members at opposite ends thereof cooperating respectively with the shoulders of the body and truck bolsters, the shape of one of the head members and the cross section of the pin receiving openings being such that the head may be inserted therethrough while in one position but is prevented from passing therethrough when given a partial turn, and wherein the locking member serves to lock the connecting member against rotation with respect to one of the bolsters, thereby preventing displacement of the connecting member to the position where the last named head thereof will pass through the pin receiving openings, thereby maintaining the bolsters locked against separation while permitting relative rotation thereof.

Other objects of the invention will more clearly appear from the description and claims hereinafter following.

In the drawing, forming a part of this specification, Figure 1 is a top plan view of a portion of a body bolster of a railway car illustrating my improvements in connection therewith. Figure 2 is a vertical, sectional view corresponding substantially to the line 2—2 of Figure 1. Figure 3 is a vertical, sectional view in a plane substantially at right angles to the sectional view shown in Figure 2.

And Figures 4 and 5 are horizontal, sectional views corresponding respectively to the lines 4—4 and 5—5 of Figure 2.

In said drawings, 10 designates the body bolster and 11 the truck bolster of a railway car. The body bolster is provided with the usual bearing projection 12 at the bottom side thereof cooperating with a bearing seat provided on a bearing block 13 mounted in a pocket 14 at the top of the truck bolster. The cooperating bearing surfaces of the bearing member 12 and the block 13 are preferably of spherical contour. The bearing block 13 is provided with the usual upstanding annular central flange 15, which engages within a seat 16 provided in the bearing projection of the body bolster.

In carrying out my invention, I provide the body and truck bolsters and the bearing block 13 with aligned center pin receiving openings 17, 18 and 19 respectively. The openings 17, 18 and 19 are of similar cross section, each being elongated transversely, as clearly shown in Figures 4 and 5. The narrow portion of each opening is indicated by 20 and has opposed curved cylindrical wall members 21—21. The laterally elongated portion of each opening is indicated by 22 and also has opposed cylindrical wall portion 23—23. The wall portions 21—21 and 23—23 are preferably concentric, as clearly shown in Figures 4 and 5. Above the opening 17, the body bolster is provided with a pocket 24 which is preferably of cylindrical cross section and of a diameter corresponding to the diameter of the laterally elongated portion of the opening 17. Inasmuch as the pocket 24 is of greater diameter than the narrow portion 20 of the opening 17, opposed ledges or shoulders 25—25 are left at opposite sides of the opening 17, as clearly shown in Figures 1 and 2. The truck bolster is also provided with a pocket below the opening 18 thereof, the pocket being indicated by 26. This pocket is defined by the vertical spaced web members 27—27, which join the top and bottom sections of the truck bolster 11. The pocket 26, as most clearly shown in Figure 2, preferably corresponds in width to the diameter of the transversely elongated portion 100

22 of the opening 18. Inasmuch as the portion 20 of the opening 18 is of lesser diameter than the portion 22, shoulders 28—28 are defined at the lower end of the opening 18.

5 My combined locking center pin proper comprises a main pin member A and a locking member B. The member A comprises a shank portion and a head 29 at the bottom end thereof. Adjacent the head 29, the shank portion 10 is of substantially cylindrical cross section, as indicated at 30, the diameter of this portion being such that the same fits between the walls 21—21 of the smaller portion of the pin receiving opening 18 of the truck bolster, and 15 the pin receiving opening 19 of the bearing block 13. The portion 30 of the shank is hollow, as indicated at 31, the opening therethrough extending through the head 29 also. Above the portion 30, the shank of the member A comprises two spaced arms 32—32 having an opening therebetween corresponding to the opening 31 of the shank portion 30. The outer surfaces of the arms 32—32 are curved to correspond with the cylindrical portion 30 of the shank and are in alignment therewith and fit the smaller portion 21 of the opening 17. The arms 32—32 extend above the shoulders 25—25 of the body bolster and have lateral enlargements 33—33 at the upper 20 ends thereof forming the upper head of the member A. The enlargements 33—33 fit between the opposed curved wall portions of the pocket 24 of the body bolster and are of a length corresponding substantially to the length of the flanges 25—25 so that when the enlargements are alined with the flanges they will be co-extensive therewith. The enlargements 33 are slightly smaller than the elongated portions of the pin receiving openings 25 so that they will readily pass through the same when entering the pin member A upwardly through the truck bolster. The head 29 is preferably of annular form and cooperates with the shoulders 28 to prevent upward displacement of the member A.

50 The locking member B has a relatively wide shank portion 34 at the upper end thereof corresponding substantially in cross section to the cross section of the laterally elongated portion 22 of the opening 17. As most clearly shown in Figure 4, the central portion of the shank of the member B is of such a size as to fit between the fingers 32—32 of the member A. The bottom end 35 of the 55 shank of the member B is of reduced cross section and of substantially cylindrical form and is telescoped within the opening 31 of the shank portion 30 of the member A. As will be evident, the upstanding fingers 32—32 of the member A reinforce the shank of the member B and the cylindrical extension 35 at the bottom end of the member B, which is located within the opening 31 of the member A, reinforces the shank of the latter at this 60 point. As will be evident, the member B is

applied by inserting the same downwardly through the opening of the body bolster and is held in position by resting on the upper end of the cylindrical section 30 of the shank of the member A. The top of the member B is substantially flush with the upper ends of the arms 32—32 of the member A, as clearly shown in Figures 2 and 3. In order to facilitate removal of the member B, the same is provided with an eye portion 36 at the upper 70 end thereof.

75 In applying my improved combined locking center pin to the body and truck bolsters of a railway car, the member A is inserted within the pin receiving openings of the bolsters by 80 passing the same upwardly through the truck bolster, the enlargements 33—33 being alined with the laterally elongated portions of the pin receiving openings so that the head at the upper end of the member A will pass freely through said openings. After the member A has been completely inserted and occupied substantially the position shown in Figure 2, the member is rotated about its axis through an angle of 90° so as to register the enlargements 33—33 at the upper end with the shoulders 25—25 of the body bolster. When in this position, the member A prevents separation of the bolsters, the head 29 85 cooperating with the shoulders 28 of the truck bolster and the head at the upper end thereof, formed by the enlargements 33—33, co-operating with the shoulders 25—25 of the body bolster. In order to prevent displacement of the enlargements 33—33 of the member A with respect to shoulders 25—25 of the body bolster, the locking member B is employed. This member is inserted downwardly through the opening of the body bolster, the central portion of the shank thereof being passed between the fingers 32—32 of the member A and the laterally enlarged shank portion 34 entered into the laterally elongated portion of the opening 17 of the body bolster. The member B is forced downwardly until the cylindrical portion 35 thereof is telescoped within the opening 31 of the member A, the parts then being in the position shown 90 in Figure 3. As will be evident, the member B by engagement within the laterally elongated portion of the opening 17 of the body bolster and by engagement with the fingers 32—32 of the member A prevents relative rotation between this bolster and the assembled pin.

95 To separate the bolsters, the member B is first removed by lifting the same through the opening of the body bolster. After the member B has been entirely withdrawn, the member A may be freely rotated. The member A is then rotated through an angle of 90° so as to aline the enlargements 33—33 of the fingers 32—32 with the laterally elongated portions of the pin receiving openings. When in this position, the member A may be 100 105 110 115 120 125 130

dropped through the openings of the bolsters, thereby permitting separation of the latter.

I have herein shown and described what I now consider the preferred manner of carrying out my invention, but the same is merely illustrative and I contemplate all changes and modifications that come within the scope of the claims appended hereto.

I claim:

- 10 1. In car construction, the combination with body and truck bolsters having alined center pin receiving openings, each bolster having a shoulder adjacent the outer end of its opening; of a connecting member insertible through the opening of one of said bolsters into the opening of the other bolster, and a locking member insertible through the opening of the last named bolster into the opening of the other bolster, each of said 20 members having a shank extending through said openings, the connecting member having head elements at opposite ends thereof having shouldered engagement with the shoulders of the respective bolsters, the shape of one of said members and the cross section of the openings being such that said head may be inserted therethrough while in one position, but is prevented from passing therethrough when given a partial turn, said locking element engaging one of said bolsters and said connecting member to prevent relative rotation of the connecting member with respect to said bolster when the connecting member is so positioned that the last named 30 head thereof will not pass through the pin receiving openings, and the shank of said locking member being embraced and reinforced by the shank of the connecting member.
2. In car construction, the combination with body and truck bolsters having alined center pin receiving openings, each bolster having a shoulder adjacent the outer end of its opening; of a connecting member having a shank portion extending through the openings of the bolsters, and head members at opposite ends thereof, the shape of one of said head members and the cross section of said openings being such that said head member 40 may be inserted therethrough while in one position but is prevented from passing therethrough when given a partial turn, said connecting member being insertible through the opening of one of said bolsters; and a locking member insertible through the opening of the other bolster in a direction reverse to that in which the connecting member is inserted, said locking member inter-locking with the connecting member and the bolster 50 through which said locking member is inserted to prevent relative rotation of the assembled pin with respect to said bolster.
3. In car construction, the combination with body and truck bolsters having alined center pin receiving openings and each bolster

having a retaining shoulder adjacent the outer end of the opening thereof, each of said openings being laterally enlarged in one direction and said shoulders being cut away in alinement with the enlarged portions of said openings, thereby providing opposed retaining ledges; of a connecting member extending through said openings, said connecting member having head portions at opposite ends thereof cooperating with the shoulders of said bolsters respectively, one of said head portions conforming in cross section to the cross sectional shape of said openings to permit passage therethrough of the same when said member is in one positon and effect interlocking of said head with the ledges of the corresponding bolster when said member is displaced to register said head with said ledges; and a locking element extending through the openings of the bolsters and having a portion thereof fitting between the connecting member and the walls of said transversely enlarged portion of the opening of one of said bolsters to lock said connecting member against rotation with respect to said bolster.

4. In car construction, the combination with body and truck bolsters having alined center pin receiving openings, each bolster having a retaining shoulder adjacent its opening, each of said openings being laterally enlarged, and said shoulders being cut away in alinement with said laterally enlarged section of the opening, thereby dividing the shoulder into spaced supporting ledges; of a pin member having a shank portion fitting the narrow portion of said openings, said member having a head at one end having shouldered engagement with the ledges of one of said bolsters and laterally projecting lugs at the other end thereof adapted to pass through said laterally enlarged portions of said openings and have shouldered engagement with the ledges of the other bolster; and a locking member fitting the enlarged portion of said openings of said last named bolster and having a shank portion telescoped with the shank portion of the first named member.

5. In car construction, the combination with body and truck bolsters having alined center pin receiving openings, each bolster having a retaining shoulder adjacent its opening, each of said openings being laterally enlarged, and said shoulders being cut away in alinement with said laterally enlarged section of the opening, thereby dividing the shoulder into spaced supporting ledges; of a pin member having a shank portion fitting within the narrow portions of said openings, said shank portion including spaced fingers, said member having a head at one end having shouldered engagement with the ledges of one of said bolsters, and said fingers having laterally projecting lugs adapted to pass

through the laterally enlarged portions of said openings and have shouldered engagement with the ledges of the other bolster when said member is displaced to bring the lugs out of alinement with the laterally enlarged portion of the corresponding opening; and a locking element having the shank extending through said opening, a portion of the shank thereof being embraced by said fingers and fitting within the laterally enlarged portion of the opening of the last named bolster to hold said pin member against rotation relative to said bolster, and another portion of the shank thereof telescoped with the main shank section of the pin member.

15 In witness that I claim the foregoing I have hereunto subscribed my name this 17th day of December, 1929.

STACY B. HASLTINE.
